FIG. 4 is a left side view of the therapeutic cushion illustrated in FIG. 1;
FIG. 5 is a right side view of the therapeutic cushion illustrated in FIG. 1;
FIG. 6 is a top view of the therapeutic cushion illustrated in FIG. 1;
FIG. 7 is a bottom view of the therapeutic cushion illustrated in FIG. 1;
FIG. 8 is a front perspective view of a therapeutic cushion, according to a second embodiment of the present invention;
FIG. 9 is a front view of the therapeutic cushion illustrated in FIG. 8;
FIG. 10 is a rear view of the therapeutic cushion illustrated in FIG. 8;
FIG. 11 is a left side view of the therapeutic cushion illustrated in FIG. 8;
FIG. 12 is a right side view of the therapeutic cushion illustrated in FIG. 8;
FIG. 13 is a top view of the therapeutic cushion illustrated in FIG. 8;
FIG. 14 is a bottom view of the therapeutic cushion illustrated in FIG. 8;
FIG. 15 is a front perspective view of a therapeutic cushion, according to a third embodiment of the present invention;
FIG. 16 is a front view of the therapeutic cushion illustrated in FIG. 15;
FIG. 17 is a rear view of the therapeutic cushion illustrated in FIG. 15;
FIG. 18 is a left side view of the therapeutic cushion illustrated in FIG. 15;
FIG. 19 is a right side view of the therapeutic cushion illustrated in FIG. 15;
FIG. 20 is a top view of the therapeutic cushion illustrated in FIG. 15;
FIG. 21 is a bottom view of the therapeutic cushion illustrated in FIG. 15;
FIG. 22 is a front perspective view of a therapeutic cushion, according to a fourth embodiment of the present invention;
FIG. 23 is a front view of the therapeutic cushion illustrated in FIG. 22;
FIG. 24 is a rear view of the therapeutic cushion illustrated in FIG. 22;
FIG. 25 is a left side view of the therapeutic cushion illustrated in FIG. 22;
FIG. 26 is a right side view of the therapeutic cushion illustrated in FIG. 22;
FIG. 27 is a top view of the therapeutic cushion illustrated in FIG. 22;
FIG. 28 is a bottom view of the therapeutic cushion illustrated in FIG. 22;
